LOW DENSITY GRANULAR OR POWDER EXPLOSIVES AND THEIR MANUFACTURE

John Whetstone, West Kilbride, Scotland, assignor to Imperial Chemical Industries Limited, a corporation of Great Britain

No Drawing. Application September 19, 1942, Serial No. 458,993. In Great Britain September 15, 1941

9 Claims. (Cl. 52—21)

1

The present invention relates to granular detonating explosive compositions of the kind in which the granules individually comprise ammonium nitrate and an easily fusible organic explosive compound in a state of intimate admixture. The invention relates more particularly to the provision of new or improved granular explosive compositions as aforesaid that have low density characteristics, and to an improved process for the production of low density granular explosives suitable for commercial blasting purposes.

Blasting explosive powders containing ammonium nitrate and organic explosive compounds are usually manufactured by grinding the solid ammonium nitrate and the organic explosive together, even when, as in the case of fusible aromatic nitro-compounds such as TNT, the organic explosive compound is easily fusible. Any additional ingredients of the composition are introduced during or subsequent to the grinding operation. Prolonged grinding is required in order to produce an explosive satisfactorily sensitive to initiation by a commercial detonator. Granulated compositions made from the resulting powders ordinarily show a bulk density of about 0.9 to 1.15 grams per cubic centimetre when cartridge under a pressure of 75 lbs. per square inch.

Low density ammonium nitrate blasting explosive powders of the kind in which the low density is not occasioned by the use of low density vegetable tissue, on the contrary, are made by lightly mixing ammonium nitrate crystal aggregates of low density with the solid oxidisable ingredients. The low density ammonium nitrate crystal aggregates facilitate the attainment of a composition initially sensitive to detonation, but must not be broken down, and low density blasting powders of this kind frequently suffer from the defect that the granules constituting them are so fragile that they disintegrate very easily when jostled, e.g. in transport, or on storage, and thereby become denser and less sensitive.

Military explosives containing ammonium nitrate and aromatic nitro-compounds can be made by coating solid ammonium nitrate with the fused aromatic nitro-compound, the explosive compositions so obtained being compressed, or cast, or cast and compressed into the ammunition in which they are to be used. They are, however, seldom sensitive to initiation by ordinary detonators, and in effecting their detonation it is necessary to employ an intermediate primer or booster whereby the detonating impulse transmitted from the detonator is enhanced. The density of such charges usually exceeds 1.4 and their

2

velocity of detonation and their negative oxygen balance are usually higher than is desirable for commercial blasting purposes.

The fusion temperature of ammonium nitrate is too high to enable it to be safely melted with fusible organic explosive compounds, but it can be reduced by the inclusion of additional materials such as salts having water of crystallisation, and by various salts and organic materials that form eutectic mixtures with it. In the manufacture of cast explosive charges, such materials, usually of an oxidising or reducing character, have been included in molten compositions comprising ammonium nitrate and organic explosive compounds, with the object of minimising the content of the organic explosive compound required to yield a composition that can conveniently be loaded. These compositions containing ammonium nitrate in a more or less completely fused condition, however, suffer from the defect that the liquified inorganic salts and the molten organic explosive constitute two immiscible liquids that can only be coarsely dispersed by agitation of the melt, so that the resulting mixture segregates rapidly before it solidifies, and the resulting cast explosive charges are of lower sensitivity to initiation than those made by coating the solid oxidising salts with molten organic explosive and may fail to propagate their detonation properly.

In the preparation of cast explosive charges such as are used for filling containers, for example shells or other projectiles, grenades, mines and the like, it has been proposed to emulsify with the aid of an emulsifying agent a highly explosive organic compound or compounds in a melt of an oxidising salt or salts, for instance ammonium nitrate with or without metallic nitrates. According to this proposal, the emulsifying agent may be a colloidal substance soluble or swellable by water and capable of increasing the viscosity of the melt, and the formation of the saline melt into which the high explosive organic compound, for instance TNT, is incorporated, may be assisted by the presence of a hydrated salt, an organic amide, or a small proportion of water, the resulting emulsified explosives being characterised by improved sensitivity to detonation and other advantages as compared with similar compositions made by a fusion process or partial fusion process without the use of the emulsifying agent. One of these advantages is that compositions of sufficient fluidity for loading into ammunition may be obtained at safe working tem-

peratures, e. g. 80 to 110° C., with a reduced proportion of the fusible high explosive compound.

Massive cast explosive charges produced according to the method of the aforementioned proposal, however, are insufficiently sensitive to be initiated by an ordinary commercial detonator, and are unsuitable for commercial blasting purposes.

It is an object of the invention to provide granular low density ammonium nitrate explosives by a fusion process employing molten fusible organic explosive compounds, which will be of suitably high sensitiveness to initiation for commercial blasting purposes, but which will be free from the aforesaid defects of the hitherto known low density explosives made from ammonium nitrate and solid organic explosives or other oxidisable ingredient of ordinary density.

According to the present invention, in the manufacture of detonating explosives suitable for commercial blasting purposes, a molten easily fusible organic explosive is emulsified, with the assistance of an emulsifying agent, in an aqueous medium that comprises a saturated solution of ammonium nitrate carrying solid ammonium nitrate in suspension and free from readily hydratable salts, this medium being adapted to yield a pourable emulsion at the emulsification temperature; the resulting aqueous emulsion is congealed into solid form and converted into granules, and the resulting granules are subsequently dried at a temperature insufficient to cause them to soften.

According to another feature of the invention, the grist of the granule is made more uniform by screening them, and according to a further feature of the invention at least the fine material rejected as a result of the screening operation is remelted to form a portion of the pourable emulsion that is congealed and converted into granules in a subsequent preparation.

In putting the invention into effect, there may advantageously be employed solid high explosive compounds melting at temperatures not appreciably in excess of the boiling point of water, but which will remain solid under ordinary hot storage conditions, for instance trinitrotoluene, tetrinitroanisol and dinitrobenzene; but there may also be employed mixtures containing high explosives of higher melting points, for example, hexanitrodiphenylamine, pentaerythrite tetrinitrate, polynitronaphthalenes or the like, with easily fusible or even liquid explosive compositions in suitable proportions to yield mixtures that will be solid at hot storage temperatures but liquify at temperatures not substantially above the boiling point of water. It is usually convenient to carry out the emulsification at a temperature between about 80° and 110° C.

As emulsifying agents there are advantageously employed colloidal substances soluble or swellable by water and capable of increasing the viscosity of the hot aqueous ammonium nitrate solution, for instance agar-agar, sodium alginate, carrageen moss extract, flour, dextrin, sodium cellulose glycolate, starch and various gums. The quantity of the emulsifying agent required will usually lie between 0.3 per cent and 0.7 per cent of the dry weight of the emulsion. The emulsification may be assisted by agitation.

If desired, ingredients of various types commonly employed in the manufacture of explosive compositions may be introduced into the composition of the emulsion, in which case they are preferably of an insoluble and infusible type. Cooling or quenching ingredients such as fluor-

spar, dolomite, or anhydrite, or oxidisable ingredients such as metal powders may thus be introduced. Fusible or soluble materials, however, can often be employed provided they do not have the property of readily forming hydrates with water or crystallisation and are not unduly hygroscopic. Examples of salts that may be employed in this way include sodium chloride and sodium nitrate. Ingredients commonly used in blasting explosive compositions, for instance carbonaceous ingredients, especially those of low density, cooling or flame-quenching agents, waterproofing agents; oxidising salts; noncarbonaceous oxidisable ingredients and so forth may also, if desired, be used in admixture with the granules obtained after the emulsion has been congealed and granulated, advantageously after they have been dried. In some cases they may be applied as surface coats to the dried granules. It will be understood that the composition of the final explosive should be so adjusted that it has a desirable oxygen balance, taking into account any wrapping or packing material that will be included in the blasting charge. It is noteworthy that if sufficient water were included in the composition to dissolve the whole of the ammonium nitrate at a temperature suitable for emulsification, the emulsion would not congeal satisfactorily when subsequently cooled, so that the granulation of the product would be impracticable. Although the fluidity of the ammonium nitrate and of the emulsion as a whole at the emulsification temperature is somewhat influenced by the nature and amount of the other non-aqueous ingredient or ingredients, we have found that in the case of a blasting explosive composition consisting of trinitrotoluene, ammonium nitrate and an emulsifying agent about 3 to 8 per cent. water should be present, so that about 30 to 60 per cent. of the ammonium nitrate remains undissolved at the emulsification temperature.

The granulation may be carried out by pouring the emulsion into the form of an extended cake or the like, and breaking up the latter mechanically into granules when it has congealed. Any particles that are too large or too small may be screened off before or after the granules have been dried off.

The waste from the screening operation may be utilised in forming another batch of emulsion, advantageously with the addition of a little water, since a certain amount of drying may have taken place by the time the congealed granules have been screened. The size of the granules may be controlled by varying the intensity of the mechanical action in breaking up the congealed cake. The bulk density of the resulting explosive depends amongst other factors on the size of the granules, but it will be understood that the invention includes not only explosive compositions of coarsely granular form, but also explosive compositions in which the granules are small, and which may be described as powders.

The granular explosives made according to the present invention are characterised by possessing desirably low density characteristics, but the granules of which they are composed are nevertheless of a robust character which enables them to maintain their desirably low density characteristics during transport and storage. These explosives also possess other desirable properties, more particularly, excellent or improved sensitiveness to initiation and low velocity of detonation. They may be used in quarrying or mining and are especially suitable on account of their

2,409,919

5

low density characteristics for use in situations where it is desired to break up the material to be blasted without effecting an intensive degree of comminution, for instance in the winning of lump coal. They maintain their solidity and low density at the climatic storage temperatures used in testing.

The unusually low density characteristics of the explosives of the present invention, however, are due not only to the granulation of the congealed emulsion, but also to the evaporation of water from the individual solid granules. In drying the granules, therefore, the temperature must not be sufficient to cause incipient fusion of the granules, which would destroy the desired porosity, but as the drying proceeds the drying temperature may, if desired, be progressively increased.

The dried granules may advantageously be provided with a coating of a waterproof material, but this is not essential. They should be packed in waterproof containers, and if the granules have not been coated it is often desirable that they should be packed in containers which will resist the entry of water vapour. It is desirable that the explosive should contain no ingredient of a marked deliquescent character.

When cooling and flame-quenching ingredients are included, explosives of suitable composition for blasting in fiery or gassy mines may also be made in accordance with the present invention.

The invention is further illustrated by the following examples, in which the parts are parts by weight.

Example 1

A mixture of 81.5 parts ammonium nitrate, 6 parts water and 0.5 part agar-agar are heated until the agar-agar has dissolved and the temperature has risen to 81 to 85° C. 18 parts trinitrotoluene are stirred in and the mixture is further heated to 90° C., by which time the trinitrotoluene has melted, and is stirred until a well dispersed pourable emulsion has been formed. The aqueous emulsion is then poured on to a cold surface to form a slab of about $\frac{1}{4}$ inch in thickness, which is crushed into granules after it has congealed, and is screened. The particles passing a No. 16 and retained by a No. 25 B. S. sieve are then dried off at 35 to 45° C. The resulting explosive when cooled and cartridge under a pressure of 75 lbs. per square inch has a bulk density of 0.7. The explosive has a power amounting to about 85 per cent. of that of blasting gelatine, reckoned on a weight basis. The explosive when initiated by a No. 6 mercury fulminate potassium chlorate detonator has a velocity of detonation of about 2400 metres per second.

Example 2

The procedure is the same as in Example 1, except that the cake of congealed aqueous emulsion is broken up into smaller particles and after these have been dried they are screened through a 25 B. S. sieve, all the coarser material being appropriately sized to provide a more coarsely granular explosive. The material passing the 25 mesh sieve when cartridge at a pressure of 75 lbs. per square inch in a waxed paper cartridge has a density of 0.8 and detonates under the impulse of a No. 6 mercury fulminate-potassium chlorate detonator at a velocity of about 2,900 metres per second. In a test in which two $1\frac{1}{4}'' \times 3''$ freshly made cartridges of the same explosive in their waxed paper wrappers are

CROSS REFERENCE

SEARCH ROOM

6

placed in line at varying distances in a common paper wrapper, the second cartridge is detonated by the first at a distance of 4" but not at 5".

Example 3

5 A mixture of 73.4 parts ammonium nitrate, 5 parts water, and 0.4 part agar-agar are warmed until the agar-agar has dissolved and the temperature has risen to 85° C. 16.2 parts trinitrotoluene are stirred in and the mixture is further heated to 90° C. and agitated until the molten trinitrotoluene has been emulsified. 10 parts anhydrite, screened to pass a 40 mesh sieve and to be retained on a 60 mesh B. S. Sieve, are then stirred into the mixture which is kept agitated. The mixture is then poured on to a cold surface to form a slab of about $\frac{1}{4}$ " thickness and crushed into small granules after it has congealed. It is dried and screened to pass a 20 mesh B. S. sieve, and the larger particles retained on the sieve are sent for remelting. When cartridge in waxed paper tubes at a bulk density of 0.8 the resulting explosive detonates under the impulse of a No. 6 mercury fulminate-potassium chlorate detonator at a velocity of 2200 metres per second. Its power is about 71 per cent. of that of blasting gelatine. In the double cartridge test described in Example 2 the second cartridge was detonated by the first at 3" but not at 4".

Example 4

20 The procedure is the same as that of Example 3 except that talc is used in place of anhydrite. The properties of the explosive are generally similar to that of Example 3.

Example 5

25 The procedure is the same as in Example 3 except that fluorspar is used instead of anhydrite. The properties of the explosive are generally similar to that of Example 3.

Example 6

30 The procedure is the same as that of Example 3 except that limestone, screened to pass a 60 mesh sieve but not to be retained on a 100 mesh B. S. sieve, is used instead of anhydrite, and that the proportions of the ingredients employed are 45 ammonium nitrate 65.2 parts, agar-agar 0.4 part, water 5 parts, limestone 20 parts, trinitrotoluene 14.4 parts. When the dried granules are cartridge under a pressure of 75 lbs. per square inch in waxed paper containers the bulk density is 0.8, and the explosive detonates under the impulse of a No. 6 mercury fulminate-potassium chlorate detonator at a velocity of about 1900 metres per second.

Example 7

35 The explosive is prepared as described in Example 3, except that the proportions of ingredients employed are as follows: ammonium nitrate 69.6 parts, agar-agar 0.4 part, water 5 parts, aluminium 15.0 parts, trinitrotoluene 15 parts. The bulk density of the explosive when cartridge under a pressure of 75 lbs. per square inch is about 0.75, and the explosive is initiated under the impulse of a No. 6 fulminate-potassium chlorate detonator with a velocity of about 2300 metres per second. The power of the explosive is about 90 per cent. of that of blasting gelatine. An explosive of similar composition made by milling together the dry ingredients has a density under 40 the same cartridge pressure of about 1.1 and

detonates with a velocity of 3600 metres per second.

Example 8

The explosive is prepared according to the method of Example 3 except that sodium chloride is used instead of anhydrite, and the proportions of the ingredients used are—ammonium nitrate 71.6 parts, sodium chloride 13 parts, water 4 parts, agar-agar 0.4 part and trinitrotoluene 15 parts. Under a cartridge pressure of 75 lbs. per square inch the bulk density of the dried granules is about 0.9, and under the impulse of a No. 6 mercury fulminate-potassium chlorate detonator, the resulting explosive detonates with a velocity of 2200 metres per second. An explosive of similar composition made by a dry milling process when cartridge under the same pressure has a density of about 1.1 and a velocity of detonation of about 3500 metres per second.

Example 9

The ingredients used for making the explosive are the same as in Example 8, but the sodium chloride is mixed with the dried granules of the solidified emulsion containing only the ammonium nitrate, agar-agar and trinitrotoluene instead of being included in the composition of the aqueous emulsion. The sodium chloride is employed in crystalline form passing a 40 mesh and retained by a 60 mesh B. S. S. sieve. Under a cartridge pressure of 75 lbs. per square inch the density is about 0.9, and the velocity of detonation is about 2600 metres per second under the impulse of a No. 6 mercury fulminate-potassium chlorate detonator. In the double cartridge test the second cartridge is initiated by the first at 4" distance but not at 5".

While in the preceding examples there is illustrated the use of a No. 6 mercury fulminate-potassium chlorate detonator, all of these explosives when freshly made are capable of being initiated by a No. 2 mercury fulminate-potassium chlorate detonator. The hereinbefore quoted numerical values for bulk density are reckoned on the basis that the bulk density of water is unity.

I claim:

1. A process for the manufacture of low density blasting explosives which comprises emulsifying a molten easily fusible organic explosive with the assistance of an emulsifying agent in an aqueous medium that comprises a saturated solution of ammonium nitrate carrying solid ammonium nitrate in suspension and is free from readily hydratable salts, this medium being adapted to yield a pourable emulsion at the emulsification temperature, congealing and granulating the resulting aqueous emulsion and drying the resulting granules at a temperature insufficient to cause them to soften.
2. A process as claimed in claim 1 wherein the granulation is carried out by pouring the emulsion into the form of an extended cake or the like and breaking up the latter mechanically when it has congealed.
3. A process as claimed in claim 1 wherein the fusible organic explosive comprises an explosive compound melting at a temperature not substantially exceeding the boiling point of water.
4. A process as claimed in claim 1 wherein the fusible explosive comprises a mixture of compounds that fuses at a temperature not substantially exceeding the boiling point of water, of which one constituent is a compound melting at a temperature substantially exceeding the boiling point of water.
5. A process as claimed in claim 1 wherein the fusible explosive comprises trinitrotoluene.
6. A process as claimed in claim 1 wherein the emulsification is carried out at a temperature between 80° C. and 110° C.
7. A process as claimed in claim 1 wherein the quantity of emulsifying agent employed amounts to from 0.3 to 0.7 per cent. of the dry weight of the emulsion.
8. A process as claimed in claim 1 wherein the emulsion consists of a mixture of ammonium nitrate, trinitrotoluene, an emulsifying agent and from 3 to 8 per cent. of water reckoned on the weight of the emulsion.
9. A process as claimed in claim 1 wherein the ammonium nitrate composition contains a metal powder.

JOHN WHETSTONE.
